UNITED STATES PATENT OFFICE.

NICHOLAS FANCHER, OF JOHNSTOWN, NEW YORK.

GLOVE-CASE.

SPECIFICATION forming part of Letters Patent No. 690,937, dated January 14, 1902.

Application filed August 20, 1901. Serial No. 72,633. (No model.)

To all whom it may concern:

Be it known that I, NICHOLAS FANCHER, a citizen of the United States of America, and a resident of Johnstown, Fulton county, State 5 of New York, have invented certain new and useful Improvements in Glove-Cases, of which the following is a specification.

My invention relates to devices for displaying, retaining, and transporting gloves; and 10 the object of my invention is to provide a neat and serviceable package within which a pair of gloves may be infolded, together with a case to which several of the aforesaid packages may each be removably attached and the 15 contents thereof advantageously displayed and the case capable of being folded into a compact form for transportation. I attain this object by means of the mechanism illustrated in the accompanying drawings, in 20 which—

Figure 1 is a plan; Fig. 2, an end elevation; Fig. 3, a rear plan view of one of the packages; Fig. 4, a front plan view of one of the packages; Fig. 5, a plan view of the case folded.

Similar letters refer to similar parts throughout the several views.

The case A, constructed of leather, cloth, paper, or other suitable material, is preferably provided with an overlapping piece B B at 30 each end and projecting overlapping pieces C D E F on the sides thereof, preferably at or about midway between the ends of the case. Within the case I place a series of packages G, preferably securing them therein by means 35 of a tape, ribbon, or other fastening g, which fastening-tape passes through the packages G, preferably at or near each end, and through suitable openings in the case and is tied or fastened at the back of the case, as indicated 40 in Figs. 1 and 2.

The packages G are made up of preferably a single piece of material, cut to form leaves H J on the side, adapted to fold over on the center piece K and to be held in position by 45 the tongue h, fitting in the slot j, as shown in Fig. 4. The ends of the center piece K are preferably provided with the overlapping pieces k. For convenience in folding I preferably cut the leaves H and J near their ends, 50 as at L M. As thus arranged a pair of gloves or more than one pair, if desired, may be placed on the center portion K, the leaf J

folded over, the leaf H placed on top of the leaf J, and the tongue h fitted within the slot j. The end pieces k are then folded, fitting within 55 the openings L L and M M, respectively.

Through the center piece K, near each end, I preferably place a tape or ribbon g. For that purpose I preferably cut two parallel slots N N near each end for the passage of the ribbon, 60 as shown in Fig. 3, the ribbon then passing through corresponding openings O O in the case A and tied at the back of the case.

The case may be made to hold a half-dozen packages, as shown in Fig. 1, or any desired 65 number.

When a pair of gloves are displayed to a customer, the case is opened. The package containing the gloves is also opened, and when the gloves have been selected the package is 70 closed and the tape or ribbon untied and the package containing the gloves given to the customer, the package forming a neat and serviceable protection for the gloves, also an advertisement for the glove-dealer, since on 75 the package may be printed an advertisement when desired. Another package containing gloves may be inserted in the place of the one taken out, and in this way the case may be 80 kept filled, and the case containing the packages may be folded, as shown in Fig. 2. The overlapping pieces B at the ends of the case are folded upon the adjacent packages, respectively, and the packages are folded, preferably from each end to the center, and the 85 overlapping pieces C and E may be placed over the ends of the packages which have been folded upon that portion of the case to which they are attached, thus protecting the ends. Then the case is further folded upon 90 that portion to which the projecting pieces D and F are attached, and the overlapping portions D and F are then folded over and a portion thereof placed within the slots d f, respectively, and the case is ready for packing 95 away or transporting, as desired. As thus arranged I have produced a handsome and serviceable case for displaying and retaining gloves and have also provided a very convenient and tasty package for the retention of 100 the gloves by the customer after being sold by the dealer.

What I claim as my invention, and desire to secure by Letters Patent, is—

In a glove-case, the combination of a detachable package, consisting of a center piece; two leaves on each side thereof; a tongue on one of the leaves adapted to engage in the slot on the opposite leaf; projections at each end of said center piece adapted to engage with slots cut near the ends of each leaf; with a means for detachably securing said package in the case; projecting pieces on the side of the case adapted to fold over the ends of the sections of the case containing the

packages; with slotted openings in the back of the case into which said projections may be passed and hold the case together when folded.

15

Signed at Albany, New York, this 10th day of August, 1901.

NICHOLAS FANCHER.
